UNITED STATES PATENT OFFICE.

JAMES E. HANGER, JR., OF WASHINGTON, DISTRICT OF COLUMBIA, ASSIGNOR TO J. E. HANGER, INCORPORATED, A CORPORATION OF THE DISTRICT OF COLUMBIA.

ARTIFICIAL LEG.

1,246,590.

Specification of Letters Patent. Patented Nov. 13, 1917.

Application filed March 30, 1917. Serial No. 158,706.

To all whom it may concern:

Be it known that JAMES E. HANGER, Jr., a citizen of the United States, residing at Washington, in the District of Columbia, has invented certain new and useful Improvements in Artificial Legs, of which the following is a specification.

My invention relates to artificial legs, and pertains more particularly to the knee joint 10 thereof.

The object of my invention is to produce a knee joint in which the bearing parts may be adjusted with relation to each other for the purpose of tightening the contacting 15 surfaces to compensate for the wear produced by use, and thus adjust the action of the knee to prevent lost motion in the knee joint and to accommodate the knee action to the preference of the user of the leg. 20 Another object thereof is to produce a knee bolt carried on the lower leg section provided with cone bearings adjustably carried on the knee bolt, adapted to be fitted into complementary bearing boxes carried in the 25 thigh section and having means for locking the cone bearings in adjusted positions. A further object of the invention is to produce a perforated cone-shaped lubricant holder interposed between the bearing surfaces of 30 the thigh section and the leg section; and, a still further object of my invention is to produce a more simple, cheap and efficient knee joint for artificial legs than has heretofore been attained.

To these ends, my invention includes the combination and arrangement of component parts to be hereinafter described and more particularly pointed out in the claims.

In the accompanying drawings in which 40 like reference characters indicate similar parts,

Figure 1 is a vertical sectional view of an artificial leg provided with my knee joint;

Fig. 2 is a transverse sectional view of 45 the same; and,

Fig. 3 is a horizontal sectional view taken through the center of the knee joint.

Referring to the drawings, 1 indicates the 50 thigh section of an artificial leg, and 2 designates the lower leg section, which at its upper end fits over the lower end of the thigh section and is pivoted thereto by the knee bolt 3. Both sections are hollow at their adjacent ends, and the lower end of 55 the thigh section is rounded and provided

with a central slot 4 in the rear thereof extending from its lower extremity to a point above the knee bolt to accommodate the back-check 5.

As shown in the drawings, the bolt hole 60 in the walls of the thigh section is provided with a tapered journal box or bushing 6 corresponding with the shape of the cone-shaped bearings 7 carried on the knee bolt to be hereinafter described.

On each side of the leg section is secured a vertical bar 8, the upper end of which projects beyond the top of that section and is provided with transverse eyelets 9 opposite to each other, in which the adjustable ends 70 of the knee bolt are rigidly secured. Said knee bolt comprises the threaded stem 10 having the cone-shaped bearing 11 screwed on each end thereof extending into the eyelets on the side-bars 8. Said bolt stem is 75 also provided with a screw-threaded bore 12 at each end to receive the threaded stem of the lock screws 13 by which the knee bolt 10 and cone-bearings 11 are adjustably 80 clamped in rigid position with the side bars 8. The outer end of each of the cone-bearings is preferably provided with notches 14 by which it may be turned on the knee bolt stem with a tool to adjust its position longitudinally of the bolt stem and in relation 85 to the inner face of the bearing box carried on the thigh section. So that when thus adjusted the component parts of the bolt may be rigidly clamped in position by the lock screws.

For the purpose of lubricating the bearing faces of the cone-shaped bearing and the box in which it operates, I provide a cone-shaped perforated thimble 15 corresponding in shape to the bearing surfaces, adapted to 95 be charged with a semi-solid lubricant 16.

As shown in the drawings, the back-check 17 is secured at its lower end to the back of the lower leg section, while the opposite end is preferably bifurcated at 18, and is 100 looped back to form the eyelets 19, which are interiorly screw-threaded to accommodate the threads of the bolt stem 10. The looped end 17' of the back-check may be secured to the body portion thereof by 105 screws 19'.

A lever arm 20 is carried on said bolt stem preferably between the forked members of the back-check, and a link 22, and a wheel 23, may be carried on the outer free 110

end thereof to accommodate the looped suspender 24 for operating the knee joint.

What I claim as new and desire to be secured by Letters Patent is:

- 5 1. In an artificial leg, the combination with a thigh section and a lower leg section, of a knee bolt pivotally connecting same and rigidly connected with the lower leg section, bearing boxes carried on the 10 thigh section for said knee bolt, bearings secured on said knee bolt to be carried in said boxes on the thigh section, and means for adjustably regulating the pivotal bearings between the thigh section and the lower leg 15 section.
2. In an artificial leg, the combination with a thigh section and a lower leg section of tapered bearing boxes carried on the thigh section, a knee bolt carried on the 20 lower leg section, cone-shaped bearings adjustably secured on said knee bolt adapted to be carried in the tapered boxes on the thigh section, and means for moving said lower leg section on said bearings.
- 25 3. In an artificial leg, the combination with a thigh section and a lower leg section, of tapered bearing boxes carried on the thigh section, a screw-threaded bolt stem carried on the lower leg section, a cone-shaped bearing threaded on each end of said bolt stem, adapted to be carried when assembled in the bearing boxes on the thigh section, means for adjustably positioning said cone-bearings on the bolt stem to regulate the frictional contact between same and

the bearing boxes, and means for securing said cone-shaped bearings in fixed adjusted position, substantially as described.

4. In an artificial leg, the combination with a thigh section and a lower leg section of journal boxes carried on the thigh section, a knee bolt pivotally connecting said sections, bearings secured thereon, carried in the boxes on the thigh section, a perforated thimble interposed between the 45 faces of the bearing boxes and bearings, adapted to be charged with a lubricant material, substantially as described.

5. In an artificial leg, the combination with a thigh section and a lower leg section of tapered journal boxes carried on the thigh section, a screw-threaded bolt stem secured on the lower leg section, having screw-threaded bearings at each end, a cone-shaped bearing having a screw-threaded 50 bore therein, threaded on each end of the bolt stem, whereby the cone-shaped bearings may be adjustably positioned with relation to the bearing faces of the journal boxes, and a jam bolt threaded into the interior bore of the bolt stem for locking the bearing parts in adjusted positions, substantially as described.

In testimony whereof I affix my signature in the presence of two witnesses.

JAMES E. HANGER, JR.
